A. H. Judl,

Steam-Boiler Indicator.

No 11,525.

Patented Aug. 15, 1854.

UNITED STATES PATENT OFFICE.

ALBERT H. JUDD, OF ST. LOUIS, MISSOURI.

SAFETY APPARATUS FOR STEAM-BOILERS.

Specification of Letters Patent No. 11,525, dated August 15, 1854.

To all whom it may concern:

Be it known that I, ALBERT H. JUDD, of the city of St. Louis, in the State of Missouri, have invented a new and Phonetic 5 Safety-Gage for Steam-Boilers; and I do hereby declare that the following is a full and exact description thereof, reference being had to the accompanying drawings, making part of this specification, Figure 10 1 being a plan of the gage; Fig. 2, a vertical section of the same, together with a steam-whistle attached thereto, in the line $y-y$ of Fig. 1; Fig. 3, an elevation thereof viewed from the inside of the boiler; Fig. 15 4, a longitudinal vertical section through the center of the float; Fig. 5, a transverse section of the valve-rod in the line $x-x$ of Fig. 2.

Like letters designate corresponding parts in all the figures.

20 All floats for indicating the height of water in steam boilers, which have heretofore been constructed, have utterly failed to act as safety gages; because the valves, or indicators, intended to be put in action 25 by them, soon become stuck or fixed, by oxidation, or by the deposition and consequent cementation of mud or other earthy matter contained in the water, around them. This vital objection I completely obviate 30 in my present invention.

The first feature of my invention consists in passing the stem of the valve through an enlargement c , in its supporting tube B , by which I am enabled to give short bearings 35 to said stem, for the purpose of preventing it from becoming fastened in its bearings by oxidation or the action of the heat upon the earthy matter driven through the same, when the valve is opened, and also 40 for the purpose of producing a fuller and clearer sound, when the valve is opened, than is produced by the escape of steam through the ordinary gage cock.

The second feature of my invention consists in removing portions of the sides from that part of the valve-stem which passes through its inner bearing aperture, so as to leave narrow bearing surfaces to guide and steady the valve, for the purpose of preventing 45 said valve-stem from becoming fastened within its inner bearing aperture, and also for causing a larger volume of steam to escape and give the alarm when a lack of water in the boiler, or excessive heat of the 50 steam, causes the float to sink, substantially as hereinafter set forth.

The third feature of invention consists

in combining the valve-stem with the float, in such a manner that, when the float shall sink and open the valve, the valve-stem may 60 be detached therefrom, for the purpose of again closing the same, by simply giving a partial turn to said valve-stem by means of its lever d .

The fourth feature of my invention consists in giving an alarm, whenever the steam in the boiler is allowed to accumulate to a dangerous degree of pressure, by placing a plug of fusible alloy in an aperture in one end of the float which is connected with my 65 improved arrangement of gage cock, substantially as set forth in the following description. Instead of the ordinary gage cock, I make use of a valve, composed of a valve-rod or stem H , which slides horizontally in a suitable socket, or supporting tube B , and of a conical (or other suitable form of) shoulder, or enlargement f , near the inner end of said valve-rod, which, when pushed outwardly against said socket, 70 entirely closes the aperture thereof. Said socket consists of a tube a , with a flange on its inner end, and is inserted outwardly through the head A , of the boiler, at the proper height, till its flange fits against the 75 inside of the head. It is secured in its place by means of a nut b , which fits upon a male screw-thread cut on the outwardly projecting portion of the tube a , as shown in Figs. 1, and 2. The aperture of said supporting 80 tube is only of sufficient diameter at its inner bearing end, to allow the valve-rod to slide freely therein; but the remaining outer portion c , is considerably enlarged, in order to enable the mud and other impurities 85 collected therein, to be more readily cleared out, and to produce a clearer and fuller sound by the issuing steam, when giving the alarm. In order to give sufficient vent 90 through the contracted inner, or bearing, portion of the aperture, and to reduce the bearing surface as much as possible, that portion of the valve-stem H , which moves therein, has segments e , e , removed from 95 its sides, as shown in Fig. 5, leaving only small portions of its periphery, as bearing 100 edges, to serve in keeping the valve-stem from playing laterally, and at the same time, leave as little surface as possible to be cemented to the socket by the mud or other earthy matter which may collect around it. A handle d , is attached to the outer end 105 of the valve-stem, and serves also to limit the inward motion of the valve.

A cap G, is screwed over the outer end of the bearing tube *a*, and is provided with an aperture, which serves as the outer bearing of the valve-stem. When a steam whistle I, (Fig. 2,) is employed to give the alarm, it is inserted through this cap, as represented. But generally it will not be found necessary, as the noise of the steam rushing from the valve will ordinarily be found sufficient to attract attention. The valve-stem should either pass loosely through the aperture of the cap, or have segments removed from its sides, in the portion passing through the cap, in the same manner and for the same purposes as in the portion moving in its inner bearing aperture above described. But when a whistle is used, the vent of this outer bearing aperture should be less than that of the inner one, in order to force sufficient steam into the whistle to sound it. Both the inner and outer bearing apertures of the supporting tube should be quite short to diminish the bearing surface; and my manner of constructing the valve enables exceedingly short bearings to be used without diminishing the efficiency of the valve.

The float D, is a hollow metallic cylinder, attached, by a pivot *p*, or otherwise, to the end of an arm C, of suitable length to produce the requisite motion of the valve by the lowering of the float a given distance. The other end of said arm is secured to a suitable fulcrum-block E, the journals *l*, *l*, of which rest in bearings *h*, *h*, which may most conveniently project from, and form one piece with, the socket B, as represented. From said fulcrum-block, two prongs *i*, *i*, project vertically upward, leaving sufficient space between them to allow the portion *n*, of the inner end of the valve-stem H, to slide freely therein. At the inner extremity of the valve-stem is a flattened head *g*, arranged so that, when in a horizontal position, as seen in the drawings, the prongs *i*, *i*, will strike it, as the float descends, and draw the valve inward, but when turned up in a vertical position, it will pass between said prongs and be disengaged therefrom. The handle *d*, is so situated on the outer end of the valve-stem that, when hanging down by its own weight, as shown in the drawings, it will keep said head *g*, in a horizontal position; and when it is desired to disengage the prongs from the valve-stem and allow the float to fall, said handle is turned up one fourth of a circle, or to a horizontal position. When the water in the boiler, gets below the desired level, the sinking float D, operating through its arm C, draws the prongs *i*, *i*, inward, away from the boiler-head, and consequently separates the valve from its socket, thus causing the steam to escape and sound the alarm. The valve serves as a superior gage cock, to ascertain the state of water in the boiler; and its use

as such prevents its becoming fastened or stuck in its supporting tube, by oxidation or by the mud and other earthy matter collecting around it. For this latter purpose, it will be sufficient to start the valve once or twice a day, when a high pressure of steam is carried; and with low pressure, once in a day or two will insure safety.

Since the float D, is a hollow metallic cylinder, when an opening is made to the space inside and exposed to the water, it will of course sink. I take advantage of this circumstance, to apply a plug *m*, of fusible alloy to the float by screwing it into an aperture in one end thereof, as represented. It is made so as to melt at the maximum degree of heat which is considered safe to reach in the boiler. Should this degree of heat ever be attained, the plug would melt and allow the float to fill with water and sink; and consequently the valve would be opened and the alarm given. The float is again reached for replacing the plug, by taking out the man-head of the boiler. To stop the alarm at any time, the handle *d*, is turned up to a horizontal position, in the manner and producing the effect above described.

Having thus fully described my phonetic safety gage for steam boilers, what I claim therein as new and desire to secure by Letters Patent, is—

1. Passing the stem of the valve through an enlargement *c*, in its supporting tube B, by which I am enabled to give short bearings to said stem, for the purpose of preventing it from becoming fastened in its bearings by oxidation or the action of the heat upon the earthy matter driven through the same, when the valve is opened, and also for the purpose of producing a fuller and clearer sound, when the valve is opened, than is produced by the escape of steam through the ordinary gage cock.

2. I also claim, removing portions of the sides from that part of the valve-stem which passes through its inner bearing aperture, so as to leave narrow bearing surfaces to guide and steady the valve, for the purpose of preventing said valve-stem from becoming fastened within its inner bearing aperture, and also for causing a larger volume of steam to escape and give the alarm when a lack of water in the boiler, or excessive heat of the steam, causes the float to sink, substantially as herein set forth.

3. I also claim, combining the valve-stem with the float, in such a manner that, when the float shall sink and open the valve, the valve-stem may be detached therefrom, for the purpose of again closing the same, by simply giving a partial turn to said valve-stem by means of its handle *d*, substantially as herein described.

4. I also claim, giving an alarm, when-

ever the steam in the boiler is allowed to ac-
cumulate to a dangerous degree of pres-
sure, by placing a plug of fusible alloy in an
aperture in one end of the float which is con-
nected with my improved arrangement of
5 gage cock, substantially as herein specified.

The above specification of my phonetic

safety gage for steam boilers signed and
witnessed this fifteenth day of June 1854.
